UNITED STATES PATENT OFFICE.

FRANK H. CRUMP, OF LOS ANGELES, CALIFORNIA.

WAY-BILL.

No. 925,871.

Specification of Letters Patent.

Patented June 22, 1909.

Application filed August 11, 1908. Serial No. 447,947.

To all whom it may concern:

Be it known that I, FRANK H. CRUMP, a citizen of the United States, and a resident of Los Angeles, in the county of Los Angeles and State of California, have made certain new and useful Improvements in Way-Bills, of which the following is a specification.

My invention relates to interline way-bills employing coupons for the various connecting roads over which the freight passes, these coupons being punched simultaneously and thereby being in condition to be immediately torn off, the necessary data being impressed thereon.

Ordinarily accounting way-bills are made to cover a shipment of freight, and impression or carbon copies are sent to each road over which the freight is to pass. The original way-bill accompanies the car to its destination, and each road makes its own records from the original way-bill.

An object of my invention is to provide an interline way-bill having coupons similar to a passage ticket, which furnishes each road over which the freight passes with sufficient information to enable it to procure the proper revenue accruing from the service performed.

A further object is to avoid the multiplicity of the reports now made by both agents and conductors to cover the movement of the car, which may be kept track of by my invention in the same manner as the passengers are.

A further object of my invention is to provide a way-bill having the form and number printed thereon so as to avoid numbering each way-bill made, as is now done.

A further object of my invention is to provide a way-bill having coupons in which certain forms can be used over different routes and to different destinations, these routes and destinations being designated by a particular number, which can be punched simultaneously through all of the coupons.

My invention is illustrated in the accompanying drawings in which—

Figure 1 is a face view of the original way-bill; Fig. 2 is a face view of the duplicate card way-bill; and Fig. 3 is a view of the reverse side of the duplicate card way-bill showing the coupons attached on its lower half.

In carrying out my invention I provide an ordinary thin paper way-bill form, such as that shown at A in Fig. 1, with certain

data as the issuing road, date, route, contents, shipper, consignee, etc., etc., and detachably secured thereto is a duplicate card way-bill, like that shown at B in Fig. 2, containing the same data on its upper portion with spaces thereon to be filled in by the use of carbon paper. The original way-bill A is provided on its lower portion with spaces for the article, weight, rate, freight advances, prepay, etc. which is to be inserted after the original is removed from the duplicate card way-bill.

In the use of my improved way-bill each destination point as well as route over which the freight is to pass is arbitrarily designated by a numeral and it will be seen on examination of the two way-bills that spaces are provided for the destination number and name and the route number as well as for the roads and junctions.

Referring now to Fig. 3, it will be seen that there is a series of coupons C attached to the lower part of the reverse side D of the duplicate card way-bill, the upper part 80 of the reverse side being used for the dating stamps. A separate form of way-bill each having a form number printed thereon as shown in Figs. 1 and 2, is used according to the number of roads over which it reads; 85 for example, if it reads over two roads, form 2 with two coupons attached is used; if over three roads, form 3 is used with three coupons attached, etc., etc., one coupon being provided for each road over which the 90 shipment is to be moved. The coupons are numbered to correspond with the number of the road on the way-bill and are also provided with spaces showing complete movement of the shipment, car number, train 95 number etc. On the outer edges of each coupon are tables, the table on the right denoting the destination number and that on the left denoting the route number. These tables are so arranged as to register with the 100 route and destination tables on the face of the duplicate card way-bill so that when the route number and destination number is punched on the latter the same data will be punched simultaneously through all the 105 coupons. The coupons are secured to the lower half of the way-bill by wire stitch or otherwise and are perforated near the top to tear off easily.

Having thus described the arrangement 110 of my improved way-bill, I will indicate the manner in which it is to be used. In

entering a consignment of freight the data on the upper part of the original way-bill is filled out, the carbon impression sheet in the meantime duplicating the record upon 5 the duplicate way-bill. The lower part however, of the original way-bill, *i. e.*, that containing the table of articles, weight, rate, etc. is filled out after the original is removed from the duplicate. The original 10 way-bill is then press-copied and forwarded by mail to the agent at the destination of the shipment. Press copies are furnished the auditor of the issuing line, and a press copy is kept by the agent for file. After 15 the removal of the original way-bill from the duplicate the destination number and route number are simultaneously punched in the card way-bill and through all the coupons which are attached to its lower half. 20 The duplicate portion of the way-bill together with its attached coupon accompanies the shipments and each conductor punches and tears off his coupon and forwards it to the auditor who then has a complete record of the movement of the freight 25 and also the car.

It will thus be seen that I have provided a way-bill from which all of the necessary information pertaining to the movement 30 and accounting of freight may be obtained by each of the roads over which the freight passes but at the same time avoiding the necessity of making all the car and way bill reports ordinarily made by agents and conductors. 35

I claim:—

1. An interline way-bill consisting of an original way-bill and a duplicate card way-bill detachably secured thereto, the lower 40 part of said duplicate way-bill being provided with numerical tables suitably designated for denoting the route number and the designation number and provided on its reverse side with a series of detachable 45 coupons having tables suitably designated

as route and destination tables arranged to register with the route and destination tables on the face of said duplicate way-bill whereby the route and destination may be indicated simultaneously by punching said 50 registering tables.

2. An interline way bill consisting of an original way bill and a duplicate way bill detachably secured thereto, and having data and blank spaces on the upper part of its face the upper part of said original way bill having similar data and blank spaces adapted to register with the data and blank spaces on said duplicate way bill, the lower part of the face of said duplicate way bill being 55 provided with tables suitably designated as route and destination tables, and a series of coupons secured to the reverse portion of said duplicate way bill and provided with similar tables arranged to register with the 60 respective route and destination tables on the face thereof.

3. An interline way bill consisting of an original way bill and a duplicate way bill detachably secured thereto, and having data 70 and blank spaces on the upper part of its face the upper part of said original way bill having similar data and blank spaces adapted to register with the data and blank spaces on said duplicate way bill, the lower part 75 of the face of said duplicate way bill being provided with tables suitably designated as route and destination tables, a portion containing said data and blank spaces extending down on the lower half of said duplicate way bill between certain of said tables, and a series of coupons secured to the reverse portion of said duplicate way bill and provided with similar tables arranged to 80 register with the respective route and destination tables on the face thereof.

FRANK H. CRUMP.
